POWER TAKE-OFF

Erich H. Lichtenberg, Milwaukee, Wis., assignor
to Koehring Company, Milwaukee, Wis., a corporation

Application December 22, 1933, Serial No. 703,655

12 Claims.

(CL. 83—73)

This invention relates to power take-off means and control instrumentalities therefor, and is particularly adapted for use in connection with mixing machines, however is not limited to such specific employment and may be used in other capacities if so desired.

The teachings of this invention are especially applicable for use in connection with that class of machines known as bituminous mixers that are peculiar to other types of mixing machine in that the mixing drum is held stationary during mixing operations and agitation is obtained through power driven blades. The drum, however, is rotatable to various positions to allow the discharge and charging thereof and this invention is concerned primarily with means for so moving the drum. Heretofore this task has been carried out manually through gear and hand wheel arrangements that did not contribute considerably toward speeding up the interval of handling the material, which embraced the period beginning with loading and ending with complete discharge. To say the least, the task was laborious even though these simple mechanical devices were employed, and without doubt, movement of the drum was slow, and as a corollary to this thought, control over the drum was not positive so that it could be stopped at a predetermined point. It is to be appreciated that these mixing drums handle at least six to twelve cubic feet of material and the momentum imparted arising from the overbalancing of the load as the drum rotates to discharge position may be more than the operator can control. It is the aim of this invention then, to provide means for rotating and controlling the rotation of such a device as the mixing drum of a bituminous mixer and by virtue of which an advantageous application of power may be obtained for moving the drum to its various positions while at the same time affording means for positively controlling the momentum.

In realizing the above desideratum, I have devised a novel form of power take-off which may be driven from the prime mover of the mixer to actuate the mixing drum. In connection with this power take-off, I have devised certain control instrumentalities that in one form are effective to effect a positive application of power for rotating the heavily loaded drum to dumping position under perfect control for stopping the same at a predetermined point. This form of apparatus includes instrumentalities by means of which an instantaneous application of force may be given to the empty drum to return it

to loading position. In other words, the unloaded drum may be "kicked" to occasion the free rotation thereof to loading position. A slightly different control arrangement affords a positive application of power for rotation of the drum in one direction and stopping of the drum is made incident to the rotation thereof to a predetermined point.

Other objects and advantageous features of this invention will be found in the following detailed description and accompanying drawings, wherein like characters of reference indicate like parts, and wherein—

Figure 1 is a perspective view of a bituminous mixer embodying my novel power take-off arrangement for rotating the mixing drum, with the preferred form of control instrumentalities associated therewith.

Figure 2 is a sectional view of my power take-off unit, showing the preferred form of control instrumentalities therefor.

Figure 3 is a front elevation of the operating levers.

Figure 4 is a fragmentary view showing the positional relation of the operating parts at one stage in the operation.

Figure 5 is a front view of the power take-off unit disclosing the positional relation of the parts at another stage in the sequence of operation.

Figure 6 is a section taken on the line 6—6 of Figure 3.

Figure 7 is a fragmentary elevation showing a modified form of control mechanism for the power unit.

Figure 8 is a partial section taken on the line 8—8 of Figure 7.

Figure 9 is a section of a modified form of power take-off arrangement and operating instrumentalities.

Figure 10 is a view of the control instrumentalities for the brake of Figure 9, or 1 to 8 inclusive.

Figure 11 is a fragmentary elevation of another form of control mechanism for the unit of Figure 9.

Figure 12 is an elevation of another form of control instrumentalities for the power take-off unit.

Figure 13 is a view similar to that of Figure 12, showing the control instrumentalities in one position of adjustment.

Figure 14 is an end view of the apparatus shown in Figures 12 and 13.

As a foreword, I propose to transmit power

30

35

40

45

50

55

from a source to the drum of a bituminous mixer for rotating the same through a planetary gearing arrangement. I have proposed, however, several types of control instrumentalities for operating this planetary gearing mechanism. Accordingly, Figures 1 to 6 inclusive are devoted to the preferred form of power take-off unit embodying the planetary gear transmission mechanism and the control instrumentalities therefor. Figures 7 and 8 disclose the modified form of control instrumentalities for the power take-off unit disclosed in Figures 1 to 6 inclusive. The power take-off unit of Figure 9 is basically the same as that shown in the preceding figures, however, modifications in control instrumentalities therefor are shown in Figure 11. The remaining figures are devoted to a power take-off unit essentially the same as that proposed and shown in the other figures but which proposes still other control instrumentalities for subserving slightly different ends than that advanced for the disclosures of the other figures. Figure 10 is devoted to a brake control that may be adapted to use on any one of the power take-offs shown.

Referring specifically now to Figures 1 to 6, I have shown in Figure 1 one type of apparatus which is especially adapted to employ my novel power take-off mechanism. This apparatus is known as a bituminous mixer and embodies a motor A mounted on a chassis B which supports a mixing drum C within which is arranged an agitator D. The drum C and agitator D are mounted on a common shaft E driven by the motor A and supported in suitable bearings mounted on the framework in a manner which will be clearly apparent. For the purposes of explanation, the shaft E, Figure 2, may be considered as the main shaft in this power take-off arrangement, and upon which the various elements of the power take-off are arranged, albeit it will be understood that the shaft E may not necessarily be the main shaft of an apparatus such as that disclosed in Figure 1, and may be, if desired, a stub shaft with proper coupling arrangements for connecting the same to a drive shaft.

This power take-off arrangement mounted on the shaft E embodies a planetary gear system wherein the arresting of rotation of one part will cause the rotation of a driven part in one direction and wherein a movement of the driven part in a reverse direction is also obtained whilst the main shaft continues to rotate in one direction only.

The arrangement which I preferably employ includes a circular gear carrying member 1 mounted on the shaft E and freely rotatable with respect thereto. Endwise movement of this member off the shaft is prevented by a washer 2 retained in position by a cotter-key or equivalent means. The radial face of the member 1 is provided with a series of drilled bosses 3 for the reception of stub shafts 4 that carry the gear members 5. The arrangement and number of these gears is optional and they may be placed at 180° as disclosed in Figure 5, or at 120°, the latter arrangement embodying three of the members. The member 1 is further formed with a peripheral flange 6 upon which are mounted in side by side relation the friction band members 7 and 8 respectively, to be hereinafter mentioned. The peripheral flange 6, in this embodiment, extends inwardly and overlies a circular driven member 9 having gear teeth 10 cut on the underside of

the peripheral flange 60, said teeth meshing with the planetary gears 5. The flange 60 on the left side of the web offers a braking surface encompassed by band 61. The member 9 is keyed to the sleeve 11 of the driven member 12 by virtue of the key 14, the sleeve being in turn mounted on roller bearings 15 spacing the same on the shaft. The member 12 is disc-like in configuration and is intended to be bolted by a bolt and nut arrangement at 16 to some device to be driven, say for instance, the drum C of the bituminous mixer. To support the power unit, I have provided a bracket member 19 which may be secured to some part of the frame of the mixer or to any convenient support if the device is not employed with a mixer, and which encompasses the sleeve 11 in the zone 20. The planetary gears 5 are each in mesh with a main shaft gear 21 keyed on the shaft E which constitutes the driving gear for rotating the planetary gears and the other parts of the apparatus.

The controls for the friction band members 7 and 8 are best shown in Figures 2 to 5 inclusive, and it is to be pointed out that the controls for the band 7 are separate and independent from the controls for the band 8 albeit the controls for the band 7 are effective to operate the control for the band 8 for a particular purpose to be hereinafter brought out. Accordingly, with reference to Figs. 2 and 3, the control members for the band 7 include a lever 22 pivoted as at 23 on a support member 24 which takes the configuration shown in Figure 6 and which is drilled in its lower flange to provide apertures 25 for the accommodation of mounting bolts. The short arm of the lever 22 is pivotally connected as at 26 to the looped end 27 of the band 7 whereas the opposing looped end 28 of this same band is connected by a pin 29 to the upper end of the support 24. It will be obvious that by moving the long arm of the lever 22 downwardly, the band will be tightened about the peripheral flange 6 to arrest the rotation thereof.

The control instrumentalities for contracting the band 8 include a lever 30 mounted on a bracket 31, Figure 2, formed as a part of the member 9, the said member 30 being mounted thereon by means of a pivot pin 32. The long arm of the lever 30 is provided with a long pin 30', Fig. 2, which overlies and is intended to contact with the arm 22 when the same is in a substantially horizontal position as shown in Fig. 3. The short arm of the lever 30 is connected by a pin 33 to the looped end 34 of the band 8. The opposing end of the band 8 is connected by a pin 35 to the bracket member 31. Obviously by moving the long arm of the lever 30 upwardly the band 8 is caused to contract and grip the peripheral flange 6.

A drilled boss 20' on the support 19 receives a pin 64 which pivotally supports an operating handle 63 for the brake band 6, Figure 10. The handle is in the form of a bell crank and the short arm 65 is connected at 66 to one end of the band and the other end is anchored at 62 on the support.

To trace the operation of this power take-off unit, in rotating the drum, I will start with the drum in the position of Figure 1, namely, the loading position or the position which it occupies during the mixing period. Let it be pointed out that the relative positions of the parts of the power take-off controls, particularly the small lever 30, is as shown therein, with this lever lying in the upper right quadrant of the circle. When

the lever 22 is pressed downwardly to tighten the band 7, the rotation of the disc 1 is stopped and the planetary gears 5 are compelled to rotate about their axes in a counter-clockwise direction, 5 assuming that the main gear 21 is rotating in a clockwise direction. As a result, the member 9 Figure 2, will be rotated in a counter-clockwise direction, thus moving the small lever 30 to the left as well as the mixing drum, and the lever 22 is held down until the drum reaches proper discharge position. At this time the lever 30 should be in the vicinity of the lever 22 as shown in Figure 3 and stopping of the drum is obtained through the brake lever 63 and associated band 64. It is of importance that the lever 30 be not tripped at this time and that it come to rest either in engagement with the lever 22 or in such position that it may be engaged and actuated by the lever 22. The drum is now in a position 10 to empty and after the contents have been discharged therefrom, it is desirable to return the unloaded receptacle to the position shown in Figure 1, where it may be recharged for subsequent mixing operations. To so return the 15 drum, the lever 22 is lifted upwardly by the operator after first releasing the brake, whereupon the long arm of the lever 30 is lifted and the band 8 tightened. As the band 8 tightens, the rotation of the member 1 is stopped and the 20 planetary gears 5 are locked with respect to the main shaft gear 21 and the internal gear 10, Figure 2, whereupon the whole planetary gearing assembly is rotated in a clockwise direction with the shaft E. With the parts so locked, the 25 planetary gearing arrangement does not operate as such for transmitting motion so that it may be said that it is rendered inoperative for this phase of transmitting power. To continue, as long as the small lever 30 is under the influence of the 30 lever 22, force will be transmitted to the drum for rotating it to loading position. This action imparts a "kick" to the drum and as soon as the lever 30 is carried above the lever 22 the band 8 is released and the drum is free to rotate under 35 its own momentum to loading position where it is stopped through the use of the braking elements disclosed. As soon as the band 8 is released, the planetary gearing mechanism is restored to 40 idle position and is not effective to transmit power. Obviously, by this arrangement I obtain a positive application of force for moving the 45 heavily loaded drum to discharging position, and I control the momentum so that the drum cannot get out of hand and move past discharging position through the power take-off unit as well as the braking instrumentalities.

I propose an alternate control arrangement for the power take-off unit of the type shown in Figures 1 to 6, and reference may be had to Figures 7 and 8 as disclosing the arrangement. In this showing the support 24 mounts a lever of the first class having its fulcrum in the middle on the pin 40, the lever having a short arm 41 and a long arm 42. In this instance the lever is provided with a bifurcated part 43 pivotally connected by a bolt member 44 to one end of the brake band 7. The other end of the brake band is connected as at 45 to the support 24. Obviously, by pulling up on the long arm of the lever, the brake band is contracted to grip the peripheral flange and accomplish the rotation of the mixing drum to the left, or in a counter-clockwise direction, as hereinbefore set out. A slightly different control arrangement is shown for the band 8, and the support 31 of Figure 2 which is

dependent from the part 9 is extended into a handle 46 to be conveniently grasped by the operator. The end 31' of the brake band 8 is connected by the pin 35 to the support member in the zone above the handle as shown in Figure 7. 5 Mounted on the handle is a lever 50 pivoted at its midpoint as at 51 and which is connected on the short arm side as at 52 to an adjusting screw arrangement 53 connected to the other end 34 of the band. Obviously, by raising the long arm 10 of the lever 50 the band 8 may be tightened. This may be accomplished by pressing downwardly on the lever 42 which brings the short arm portion 41 to engagement with the pin 50' mounted on the long arm of the lever 50. This 15 will effect a reverse rotation of the drum in the manner described with regard to the device of Figures 1 to 6, wherein a "kick" is imparted to the drum for effecting the free rotation thereof to loading position. 20

On the other hand, by moving the handle 46 downwardly, the end of the lever 50 may be brought into engagement with the lever 41, Figure 7, and as pressure is further placed on the handle 46 the lever 50 will pivot on the pin 51 and draw 25 the ends of the band 8 together and lock the planetary gear mechanism for clockwise rotation with the main shaft. Hence, the drum may be "kicked" in a clockwise direction by operation of either handle 46 or lever 42. The brake of Figure 30 10 may be incorporated with the assembly and operated in the manner and for the purposes set out with respect to the assembly of Figures 1 to 6.

I have shown in Figure 9 a planetary gearing assembly that is essentially the same as that 35 shown in Figure 2 except that it does not incorporate the braking arrangement of Figure 10. It is my intention to mount the brake directly upon the peripheral flange of the member 9 that overlies the gear 10. In other words, the planetary gearing assembly shown in Figure 9 is intended for a "one direction drive", and all of the braking. Accordingly, the elements of the power take-off shown herein will be identified by 40 numeral only since they have already been described in the description of Figures 1 to 6. The control instrumentalities for operating this power unit are of two kinds, one form being shown in Figure 11 and another form being shown in Figures 13 and 14. These control apparatus have 45 one feature in common and that is that only a single lever is employed for both clutch and braking operations. In the disclosure of Figure 11 the operation of the brake and clutch is entirely manual, whereas in Figures 13 and 14 the operation 50 of the clutch and brake may be made incident to movement of the drum. I will first take 55 up the control instrumentalities disclosed in Figure 11.

It will be observed in Figure 9 that the planetary gear carrying disc 1 and the driven member 9 are of substantially the same diameter and each mounts a friction band identified by the numerals 7a and 8a. The band 7a may be called the clutch band and the band 8a the brake 60 band, and the operation of these bands is obtained through a single lever 14, Figure 11, that is pivotally mounted upon a support 73 that is 65 similar in construction to the support 24 shown in Figure 6 and is possessed of the necessary 70 apertures (not shown) for bolting the same to the frame of the machine as disclosed in Figure 1. This bracket is preferably S-shaped and in the upper zone is provided with two inclined ears that receive pins 77 and 78 respectively, the pin 75

77 retaining the looped end of the band 8a and the pin 79 retaining the looped end of the band 7a. The lever 74 which is pivoted at 75 has a short arm portion which is preferably bifurcated and mounts a long pin 76 which receives the other looped ends of the bands 7a and 8a. With this arrangement, when the lever 74 is moved downwardly in the direction of the arrow, the band 8a is contracted, whereas the band 7a is open to thereby apply a braking force on the member 9 and hence arrest the rotation of the mixing drum or hold it positively against rotation. When the lever 74 is lifted in the direction of the arrow, the band 8a is opened and the band 7a contracted to stop the rotation of the part 4, whereupon the planetary gears 5 are compelled to rotate about their respective axes and the driven part 9 is rotated in a counter-clockwise direction to rotate the drum from loading to unloading position. The brake 8a may be applied to stop the drum and hold it in proper unloading position. The drum may then be returned to loading position manually, or, in the event the nature of the mixing apparatus will allow the 25 complete rotation of the drum, power may be again applied through the planetary gear mechanism to rotate the drum through the remainder of the 360° back to loading position. The small spring shown at 76a is merely for the purpose of holding the lever 74 in a horizontal or inoperative position.

Referring now to Figures 12 to 14 inclusive, I have shown therein a control arrangement for the planetary gearing assembly of Figure 9 which preserves the thought of single lever operation for both clutch and brake and has the additional feature of being operated by the drum of the mixer. The support member for this arrangement differs slightly over that of previous arrangements and consists in a member 80 which is to be mounted on the frame of the mixing machine and which has an angularly disposed extension 81 drilled at its end for the reception of a pin 82. The pin 82 mounts the operating member 83, the long arm of which is curved as shown in the illustration in the direction of its length and also in the direction of its width to provide an offset end 84 lying in the vicinity of the mixing drum, see Figure 14. This operating end of the handle is intended to be engaged by an abutment member 85 that is formed as a part of the mixing drum and projects outwardly from the radial face 86 thereof as shown. The function of this abutment member will be taken up 50 hereinafter.

The short arm 87 of the lever 83 forms, with a lever 88 pivotally connected thereto at 89, a toggle arrangement for operating the clutch mechanism through the band 7a. With reference to Figure 14, it will be observed that the toggle lever 88 is pivotally secured to a plate member 90 which forms one element of an assembly generally indicated by the reference character N, mounted upon a pin 91 that is in turn mounted 65 upon the support 80 and secured thereto by a nut 92. Now this assembly N includes a second plate 93 which is drilled to receive in spaced relation three rods, 94, 95, and 96, the opposite ends of which are located in the plate 93. This assembly N is intended to rock about the member 91, which defines the axis of rotation, under the urging of the lever 88. The toggle lever 88 is connected to the assembly through engagement with the rod 95 which is extended beyond the 75 plate 93. The rod 95 also acts as an anchor for

one end of a contraction spring 97 and is connected at its other end to the pin 82.

In connecting the bands to this assembly, the connecting rod 98 is sleeved on the rod 96 and attached by means of a nut to one end of the band 8a. The other end of this band is anchored on the center-pin 91. Likewise, a connecting rod 99 is bolted to one end of the band 7a and connected to the rod 94 at its other end and the other end of this band 7a is mounted on the 10 center pin 91.

With reference to Figure 12, it will be observed that the spring 97 is intended to lie in a straight line position between the pin 82 and the rod 95 so as to bias the toggle toward collapsed 15 position on either side of a center line drawn between the pin 82 and rod 95. The spring will act to collapse the toggle on either side of its "on-center" position.

As for the operation, assuming that the mixing drum is in the position shown in Figure 1, in readiness to be moved to the left for unloading, the lever 83, which is preferably in the full line position shown in Figure 12, is moved upwardly to the upper dotted line position which 25 flattens the toggle arrangement and shifts the plate assembly to the lower dotted line position shown, thus tightening the clutch band 7a and stopping the rotation of the gear carrier 4 to effect the rotation of the driven part 9 and the 30 drum in a counter-clockwise direction. In fact, when the lever 83 is thrown to its upper dotted line position, the toggle is moved to the left of its center and the spring is effective to retain the toggle in such position to continue the operation of the planetary gearing assembly. Rotation of the drum to the left eventually brings the abutment member 85 into engagement with the operating end 84 of the lever 83, whereupon the end of the lever is swung downwardly until 40 such time as the toggle is shifted to the right and beyond the center-line between the pins 82 and 95. When the toggle passes over dead-center, the spring is immediately effective to initially set the brake since it tends to collapse the 45 toggle and move the plate assembly toward the upper dotted line position of Figure 12. Continued rotation of the drum, which may arise from the momentum imparted during the positive rotation, moves the lever 83 to its lower 50 dotted line position, which sets the brake and brings the drum to a stop at the proper position for unloading. The proper drum position for unloading may vary with mixers of varying type, and hence, the positional relation between the 55 abutment 85 and the lever 83 should best be determined in actual practice.

In returning the drum to loading position, it may be first started manually by lifting up on the operating end of the lever 83 which releases the brake and urges the drum about its axis. The drum may then be pushed by hand to loading position. If desired, the operating lever 83, Figure 14, can be sprung inwardly to disengage the abutment and then lifted to upper dotted line position of Figure 12 to release the brake and apply the clutch to rotate the drum through the remainder of the 360° to loading position.

I have described this power take-off unit in 70 the environment of a bituminous mixer. As before mentioned, these mixers embody a main driven shaft for the agitator and the drum axis of rotation is the same as that of the shaft. However, in some constructions the drum is sup- 75

ported directly by the heavy framework and the shaft bearings are relieved of the weight of the drum. The main point to make is that the drum and shaft are independently rotatable, except 5 when coupled through the mechanism herein disclosed.

Having thus described my invention, what I claim as new and desire to secure by Letters Patent of the United States, is—

10 1. In combination with a mixing apparatus of the class described, which includes a frame, a mixing drum mounted on said frame, a driven shaft lying on the axis of rotation of said mixing drum, a prime mover mounted on said frame for rotating said shaft, a power take-off means for coupling said shaft to said drum for selective rotation of said drum, said power take-off including a gear carrier mounted on said shaft and freely rotatable with relation thereto, a plurality of planetary gears mounted on said gear carrier, a gear mounted on said main shaft and meshing with said planetary gears, a driven member mounted on said shaft and having a gear meshing with said planetary gears, a sleeve member encompassing said shaft and supporting said driven member, said driven member being keyed thereto, a radial part on said sleeve member, instrumentalities for connecting said radial part to said drum, a support for said sleeve encompassing said sleeve between the radial part and the driven member, and a pair of friction bands, one of which is mounted on said driven member and the other of which is mounted upon said gear carrier, and operating instrumentalities 30 for effecting the drive of said drum through said planetary gearing, driven member and sleeve member.

2. In a mixing apparatus of the class described, a rotatable mixing drum, and means for rotating said drum, comprising a multi-part planetary gear mechanism including means for locking the parts of the gear mechanism against relative movement, said last named means comprising a friction band mounted on and carried by one of said parts and releasably connected to another of said parts, control instrumentalities for said friction band, a second friction band for controlling the operation of the planetary gear mechanism, control instrumentalities for said second named friction band, the control instrumentalities of said first named friction band being movable into and out of a position for engagement with the control instrumentalities of the second named friction band.

3. In combination with a rotatable mixing drum, means for rotating said drum, including a driven part, and means for releasably connecting said driven part to said drum, said means including a friction band coupled for rotation with said drum and adapted to be contracted about said driven part for rotation therewith, actuating instrumentalities for contracting said friction band, and means for operating said actuating instrumentalities, said actuating instrumentalities being movable into a position for engagement with said last named means and separable therefrom when actuated thereby, said arrangement being of such a nature that when the friction band is contracted about said driven part the drum is connected for rotation in one direction and upon separation of the actuating in-

strumentalities and the means for operating the same, the friction band is released and the drum is free to rotate under its own momentum.

4. In combination with a rotatable mixing drum and means for rotating said mixing drum, a control for said means which comprises a pair of friction bands, one of which is rotatable with respect to the other, operating instrumentalities for each control band, said operating instrumentalities including a pair of pivoted levers, one 10 of said pivoted levers being associated with the movable band and being movable into and out of a position for engaging with the other lever, said arrangement being of such a nature that the movable band is actuated by the other of said 15 levers through engagement with the lever of the movable band and movement of said movable band effects disengagement of said levers.

5. In a mixing apparatus of the class described which includes a rotatable mixing drum, a driven shaft and a prime mover for rotating said shaft, means for coupling said drum to said shaft for effecting the rotation of said drum which comprises a multi-part planetary gear mechanism, one of said parts being rotatable relative to another of said parts, means for locking said parts together for simultaneous rotation, said means comprising a friction band supported by one of said parts and adapted to be contracted about the other of said parts and to rotate therewith, 30 a second friction band encompassing one of said parts and adapted to be contracted therearound, actuating instrumentalities for each of said bands, the actuating instrumentalities of the coupling band being movable therewith and toward and away from the other actuating instrumentalities, said first named actuating instrumentalities being operated by said second named actuating instrumentalities and separable upon actuation, whereby said mixing drum may be 40 connected for rotation in one direction.

6. In combination with a rotatable mixing drum, means for rotating said drum, including a driven part, and means for releasably connecting said driven part to said drum, said means including a friction band coupled for rotation with said drum and adapted to be contracted about said driven part for rotation therewith, actuating instrumentalities for contracting said friction band, and means for operating said actuating instrumentalities, said actuating instrumentalities being movable into a position for engagement with said last named means and separable therefrom when actuated thereby, said arrangement being of such a nature that when the friction band is contracted about said driven part the drum is connected for rotation in one direction, and upon separation of the actuating instrumentalities and the means for operating the same, the friction band is released and the drum is free to rotate under its own momentum, and a friction brake for controlling the rotation of said drum.

7. In a mixing apparatus, a mixing drum, a driven shaft, means for coupling and uncoupling said drum to said shaft, a brake associated with said means for controlling the momentum of said drum, and a single lever for operating said brake and said means by the rotation of said drum.

8. In a mixing apparatus, a rotatable mixing drum, a driven shaft, a planetary gear mechanism for coupling and uncoupling said shaft to said drum, a brake associated with said planetary gear mechanism for controlling the momentum of said drum, and a single lever for control- 70 75

ling the operation of the planetary gear mechanism and said brake, said lever being operable by the rotation of the drum.

9. In a mixing apparatus, the combination with 5 a rotatable mixing drum and a driven shaft, means for connecting said drum to said shaft, control instrumentalities for said means including a friction band and a lever for operating said band, a brake for arresting rotation of said drum, 10 including a friction band, instrumentalities for connecting said last named friction band to said lever, and means on said drum for engaging said lever to move the same to operate said friction bands incident to rotation of said drum.
- 15 10. A mixing apparatus which includes a rotatable mixing drum having a charging opening and wherein the drum is movable from one position to another to bring the charging opening to a position wherein the contents of the drum 20 may be discharged, a driven shaft, means for coupling said shaft to said drum for moving the same to bring the opening therein into positions for charging and unloading, an abutment on said drum, control instrumentalities for operating said 25 means, including a lever adapted to be engaged by said abutment, a brake associated with said means, instrumentalities connecting said brake to said lever, said arrangement being of such a nature that as the drum is rotated to bring the 30 charging opening into a position for emptying, the lever is engaged by the abutment and actuated thereby to render the means inoperative for coupling the drum to the driven shaft and for applying the brake.
- 35 11. In apparatus of the class described, a rotatable mixing drum, means for rotating said drum in one direction, and means for imparting momentum to said drum effecting rotation of

the drum in the opposite direction, said last mentioned means automatically becoming inoperative after imparting a momentary initial positive rotation to said drum, but allowing said latter rotation to continue after the momentum imparting means aforesaid has become inoperative. 5

12. In a power take-off unit, a drive shaft, a gear fixed thereto for rotation therewith, a driven member freely rotatable on and wholly supported by said drive shaft and having an internal ring gear concentrically disposed about the gear on the drive shaft but in spaced relation to said latter gear, a planetary gear-carrying member also freely rotatable on said drive 15 shaft, planetary gears carried thereby and disposed intermediate the ring gear of the driven member and the fixed gear on the drive shaft and having operative driving relation with said gear on the drive shaft and with said driven member, 20 brake means operatively associated with said planetary gear-carrying member and being actuatable to cause relative movement between said planetary gear-carrying member and said drive shaft, whereby power will be transmitted from 25 said drive shaft to said driven member for rotating the driven member in one direction through said gear on the drive shaft, said planetary gears, and said ring gear; said driven member being provided with a radially extending arm, 30 in combination with additional brake means operatively associated with said planetary gear-carrying member, and instrumentalities carried by said radially extending arm for controlling said latter brake to effect rotation of the driven 35 member in the opposite direction.
